UNITED STATES PATENT OFFICE.

THOMAS R. OSBOURN, OF PHILADELPHIA, PENNSYLVANIA.

APPARATUS FOR QUENCHING COKE.

SPECIFICATION forming part of Letters Patent No. 469,868, dated March 1, 1892.

Application filed March 9, 1891. Serial No. 384,360. (No model.)

To all whom it may concern:

Be it known that I, THOMAS R. OSBOURN, a citizen of the United States, residing in the city and county of Philadelphia, and State 5 of Pennsylvania, have invented certain new and useful Improvements in Apparatus for Quenching Coke, of which the following is a specification.

According to the practice hitherto in vogue, 10 the coke has been quenched by the direct application of water to the mass within the oven within which the coking operation has been conducted.

In an application for Letters Patent, filed 15 December 17, 1890, I have described and claimed as my invention certain improvements connected with the quenching of coked coal, in which the heated coke removed from the coking oven is treated or subjected in a 20 closed receptacle to the action of steam,—small jets of water injected into the receptacle being sprayed upon the heated coke, and by contact with it converted into steam, with the resultant effect of quenching the coke.

25 My present invention has relation to my former invention, and comprehends certain improvements in apparatus for the quenching of coke by steam.

Expressed in general terms, my invention 30 comprehends a suitable receptacle, chamber, vessel, or receiving case, be its form, proportions, or dimensions, what they may, which is adapted to receive the charge of coke to be quenched, and which is wholly or in part 35 double-walled, jacketed, or incased, or so otherwise provided with a water chamber to contain water, than when the charge is introduced into the said receptacle its action of heat radiation to and upon the water in the 40 water compartment will be such as to convert the water into steam and occasion the influx of such steam into the coke-containing receptacle through such suitable apertures, orifices, pipes, or injectors, as may be necessary to place the steam generating compartment 45 in communication with the coke-containing compartment.

Obviously the mechanical embodiment of my invention may be varied, and I do not 50 restrict myself to any special form or reconstruction of it, although, in practice, such an apparatus

as is represented in the accompanying drawings and hereinafter described conveniently embodies my invention.

The apparatus in question is in the form of 55 a car in order that it may be caused to present itself in turn to the ovens of a battery of ovens, in order to receive from each its charge of coke to be quenched.

In the drawings, Figure 1 is a vertical, longitudinal, sectional, elevation on the line xx of Fig. 2 through a receptacle mounted upon wheels and embodying my improvements, and Fig. 2 a transverse sectional elevation through the same on the line of yy of Fig. 1. 60

A represents the coke-containing compartment of the car or receptacle *per se*. 65

B is the water-containing compartment or jacket, in which the water is placed and the steam generated by the action of the hot coke 70 in the compartment A, and from which the steam is discharged into said compartment A conveniently through the spraying pipes C, which are simply an ordinary form of steam-pipe placed in either compartment and communicating with both compartments. In the construction represented a series of these pipes C is employed, and the pipes are provided with a series of spraying orifices c which face and discharge into the coke-containing 75 compartment, while the inlet ends c' of the pipes open within the water compartment. In the arrangement, moreover, represented in the drawings the water compartment is subdivided by partitions b to form a series of 80 separate sub-compartments, in each of which a predetermined quantity of water is introduced, and each of which sub-compartments is separately provided with spraying pipes. This sub-division, however, is simply for convenience and not of the essence of the invention. In the car shown, I have also represented a central longitudinal water compartment B^x, which may, if desired, be dispensed 85 with or added to by the construction of transverse of otherwise disposed additional water compartments. 90

The object of additional water compartments is simply to permit of the sub-division of the coke in order that the entire mass may 100 be thoroughly subjected to the steam. The pipes shown are represented as supported by

angle irons b^x , but they may be otherwise applied and connected. Water inlets c^x are shown as applied to the water compartments.

D is the cover of the car or receptacle, represented in the construction shown to be itself provided with a water-containing compartment d provided with spraying pipes d^x with spraying orifices d' which when the cover is in place discharge into the coke-containing compartment of the car. The cover represented is dome-shaped and provided with an internal flange d^3 , so as to be adapted to be fitted air-tight upon the body of the car.

In place of the cover represented, any other form or cover may, if desired, be employed to tightly inclose the coke-containing receptacle. If desired, moreover, the car or coke-containing receptacle may be provided with a discharging door or dump formed in its bottom or walls.

The arrangement of spraying pipes represented is a convenient one, but it may obviously be modified without departure from the invention, and in the matter of the proportioning and relative disposition of the coke-containing and water-containing compartments radical variations can be made, it being, however, of prime importance that the relative disposition of the respective compartments should be such that the heat of the charge of coke can be radiated through the walls of the partitions which happen to divide the respective compartments. It is proper, also, to state that the spraying pipes are simply a typical means of communication between the water-containing and coke-containing compartments of the apparatus as a whole, and that their arrangement is to be preferably such that they are in communication with the upper portion or portions of the water compartment and with the lower portion or portions of the coke-compartment, in order that they may receive the steam near the upper part or parts of the water compartments and discharge it near the lower part or parts of the coke compartments.

Having thus described my invention, I claim and desire to secure by Letters Patent:

1. An apparatus for quenching coke by steam, consisting of a closed car, chamber, or other receptacle, adapted to contain coke, provided with a second or external wall which forms with the wall of the receptacle a closed water containing compartment or jacket to receive the heat radiated from the coke, a water supply discharging into said water containing compartment, and steam outlets leading from the upper portion of said water containing compartment and discharging into the coke receptacle, substantially as set forth. 60

2. An apparatus for quenching coke consisting of a closed receptacle or chamber embodying a compartment adapted to receive a mass of heated coke, and a series of closed independent water compartments arranged in such disposition as to expose the contents of all to the heat of the mass of coke, a water supply discharging into each water compartment, and a steam discharge from each water compartment to the coke receptacle, substantially as set forth. 7c

3. An apparatus for quenching coke which consists in a coke receiver the wall of which embodies a series of independent water compartments placed one above the other so as to expose all to the heat of a contained mass, which compartments embody liquid orifices, and water supply inlets, substantially as set forth. 75

4. An apparatus for quenching coke embodying a chamber adapted to contain coke,—a series of distinct water compartments adapted to contain water, a series of outlets arranged in the respective upper portions of the respective water compartments, and a pipe connection leading from said outlets to and discharging into the coke compartment, substantially as set forth. 80

In testimony that I claim the foregoing as my invention I have hereunto signed my name this 6th day of February, A. D. 1891. 90

THOMAS R. OSBOURN.

In presence of—

J. BONSALL TAYLOR,
F. NORMAN DIXON.
